UNITED STATES PATENT OFFICE.

JAMES ARKELL, OF CANAJOHARIE, NEW YORK, ASSIGNOR TO THE
ARKELL & SMITH, OF SAME PLACE.

DESIGN FOR A BAG:

SPECIFICATION forming part of Design No. 29,594, dated November 1, 1898.

Application filed October 1, 1898. Serial No. 692,441. Term of patent 14 years.

To all whom it may concern:

Be it known that I, JAMES ARKELL, of Canajoharie, State of New York, have invented and produced a new and original Design for 5 Bags, of which the following is a full, clear, and exact description, reference being had to the accompanying drawings, forming a part thereof.

In the drawings, Figure 1 is a view in perspective, and Fig. 2 is a view in section.

The leading feature of my design consists in a bag having the shape shown and provided with several series of longitudinal corrugations arranged at intervals throughout 15 the circumference of the cylindrical body.

A represents the bag, which is provided at intervals throughout its circumference with several series of corrugations B, and between said series of corrugations the surface of the cylindrical body is smooth and unbroken, as shown at C.

What I claim is—

The design for a bag herein shown and described.

JAMES ARKELL.
